UNITED STATES PATENT OFFICE.

MARY E. FRENCH, OF CLYDE, OHIO.

POTATO-MASHER.

No. 874,756.

Specification of Letters Patent.

Patented Dec. 24, 1907.

Application filed September 26, 1906. Serial No. 336,370.

To all whom it may concern:

Be it known that I, MARY E. FRENCH, a citizen of the United States, residing at Clyde, in the county of Sandusky and State 5 of Ohio, have invented certain new and useful Improvements in Potato - Mashers, of which the following is a specification:

My invention relates to potato mashers and has for its object the provision of a device 10 of this character constructed in such manner as to force air through the potatoes that are being mashed to render the potatoes light and fluffy.

A further object of the invention is the 15 provision of a device of this character constructed in such manner as to receive and retain liquid of any desired temperature, the body portion of the masher being constructed of a heat conducting material, by virtue of 20 which any desired temperature may be imparted to the potatoes being mashed.

Further objects and advantages of the invention will be set forth in the detailed description which now follows.

25 In the accompanying drawing: Figure 1 is a side elevation of a potato masher constructed in accordance with the invention, and, Fig. 2 is a vertical section of said potato masher.

30 Referring to the drawing, A designates a body having an opening B formed therein for the reception of water. A handle C is threaded into the upper end of this opening and is adapted to compress a gasket D 35 against the body A to form a water-tight joint. The lower face of the body portion A

is serrated or fluted, these serrations serving to effectually mash the potatoes and also confining a certain amount of air in the grooves between them as the masher is 40 forced downwardly, this air being forced through the potatoes, rendering them light and fluffy.

From the foregoing description, it will be seen that simple and efficient means are 45 herein provided for accomplishing the objects of the invention, but while the elements shown and described are well adapted to serve the purposes for which they are intended, it is to be understood that the invention is not limited to the precise construction set forth, but includes within its purview such changes as may be made within 50 the scope of the appended claims.

What I claim, is:

55 In a potato masher, the combination with a body portion having an internal opening of considerable size formed therein, said body portion being formed of heat conducting material and being adapted to contain a heating fluid and said body portion having its lower face serrated or fluted, a handle which forms a closure for the opening of the body portion at the upper end thereof, and a gasket adapted to form a fluid tight joint between said 60 handle and the body portion of the masher, substantially as shown and described.

MARY E. FRENCH.

Signed in presence of—

G. C. CRAIG,

JULIA R. CRAIG.
